Patented Dec. 16, 1919.

Inventor:
Charles A. L. Roberts
By: B. Amiger Atty.

UNITED STATES PATENT OFFICE.

CHARLES ARTHUR LLEWELYN ROBERTS, OF BIRMINGHAM, ENGLAND.

AEROPLANE-STRUT OR THE LIKE.

1,325,378.

Specification of Letters Patent.

Patented Dec. 16, 1919.

Application filed December 9, 1918. Serial No. 265,923.

To all whom it may concern:

Be it known that I, CHARLES ARTHUR LLEWELYN ROBERTS, a subject of the King of Great Britain, residing at 45 Great 5 Charles street, Birmingham, in the county of Warwick, England, have invented certain new and useful Improvements in Aeroplane-Struts or the like; and I do hereby declare the following to be a full, clear, and 10 exact description of the same.

This invention comprises improvements in aeroplane struts and the like and refers more particularly to that class of such which are of stream line section and employed for 15 the purpose of connecting the upper and lower planes.

Hitherto it has been the practice to form these struts from wood, but it is now difficult to obtain suitable material.

20 The object of the present invention is to provide a strut which can be produced other than from wood and which will be lighter than wood and have greater strength, and in accordance therewith the strut is produced from sheet metal folded to the required stream line section and provided with one or more internal webs or diaphragms for imparting the necessary rigidity.

25 Referring to the drawings:—

30 Figure 1. is a perspective view of part of a strut according to this invention.

Fig. 2. is an enlarged transverse section at A—B in Fig. 1.

35 Fig. 3. is a longitudinal section at C—D in Fig. 2.

Fig. 4. is a similar view to Fig. 2 but showing a slightly modified form of the invention.

40 In carrying this invention into practice as illustrated upon the accompanying drawings a strip of thin sheet steel is taken of a length corresponding with that of the strut to be produced, this strip being folded to provide a tube as 1 of the required stream line section, the leading edge 2 of the strut being formed by the middle of the strip, while the two edges of the strip are brought together to form the trailing edge 3 of the

strut. These two edges may extend rearwardly in contact, as shown in Fig. 1, with each other and are there welded, sweated, riveted, or otherwise connected.

The internal web or webs 4, 4 extend across the shorter diameter of the strut.

Preferably two of these internal webs are employed each formed from thin sheet metal and of channel section, their flanges 5 fitting against the inner walls of the strut and being riveted, welded, or otherwise secured thereto. These internal webs extend for the full length of the strut and are preferably pierced with a large number of holes as so as to reduce the weight to a minimum.

In practice after the main blank has been folded to the required section the internal web nearest to the leading edge would be placed in position before the trailing edges are welded, this web being riveted or welded in place. The second web is then similarly fixed and the trailing edges finally welded together.

In another construction as seen in Fig. 4 the flanges 5^a of the one internal web 4^a are extended and finally bent inwardly toward each other as 7, 8 so as to function as distance pieces for maintaining the two internal webs at the required distance apart.

While the invention is particularly applicable to the construction of aeroplane struts it is also applicable to other tubular members of stream line section for aircraft.

What I claim then is:—

In an aeroplane strut or the like, the combination of a tubular member of streamline section formed from folded sheet metal, a welded seam running the length of the trailing edge, an internal web of channel section made of sheet metal and disposed across the smaller diameter of the tube, a second internal web having extended flanges abutting against the first mentioned web forming distance pieces between the webs, and means for securing the webs in position in the tube.

In testimony whereof I affix my signature.

CHARLES ARTHUR LLEWELYN ROBERTS,
